CABINET FOR DATA PROCESSING EQUIPMENT OR SIMILAR ARTICLE

Donald D. Kelemen, Sherborn, and Charles N. Mazza,
Framingham, Mass., assignors to Honeywell Inc., Min-
neapolis, Minn., a corporation of Delaware

Filed Sept. 4, 1969, Ser. No. 19,001

Term of patent 14 years

Int. Cl. D14—02

U.S. Cl. D26—5

Fig. 1.

Fig. 2.

Fig. 3.

Fig. 4.

Fig. 5.

Fig. 6.

FIG. 1 is a perspective view taken from the top, front and one side of a cabinet for data processing equipment or similar article embodying our new design;

FIG. 2 is an elevational view taken from the side shown in FIG. 1, the opposite side being a mirror image of the side shown;

FIG. 3 is a top plan view thereof;

FIG. 4 is a front elevational view thereof;

FIG. 5 is a rear elevational view thereof; and

FIG. 6 is a perspective view taken from the top, front and one side of a modified form of the cabinet for data processing equipment or similar article shown in FIG. 1.

What is claimed is:

The ornamental design for a cabinet for data processing equipment or similar article, substantially as shown and described.
